UNITED STATES PATENT OFFICE.

JAMES E. TREAT, OF BOSTON, MASSACHUSETTS.

MECHANICAL MUSICAL INSTRUMENT.

SPECIFICATION forming part of Letters Patent No. 335,549, dated February 2, 1886.

Application filed January 5, 1884. Serial No. 116,539. (No model.)

To all whom it may concern:

Be it known that I, JAMES E. TREAT, of Boston, in the county of Suffolk and State of Massachusetts, have invented a certain new and useful Improvement in Musical Instruments, of which the following is a specification.

I will describe in detail a musical instrument embodying my improvement, and then point out the improvement in the claims.

In the accompanying drawings, Figure 1 is a sectional front view of an instrument embodying my improvement. Fig. 2 is a sectional end view thereof. Fig. 3 is a horizontal section illustrative of the construction of the case. Fig. 4 is a back view of a portion of the front of the case of the instrument, including a removable panel. Fig. 5 is a transverse section of the upper part of the instrument on a larger scale, and illustrating the manner in which the case and the key-board may be adjusted to facilitate access to devices which are normally inclosed by the case. Fig. 6 is a rear view of a portion of the upper part of the instrument on the same scale as Fig. 5. Fig. 7 is a plan view showing a means of connecting certain circuit-wires. Fig. 8 is an elevation illustrating the same parts. Fig. 9 is a detail view illustrating parts whereby the electric circuits are operated when playing with the manual keys. Fig. 10 is a sectional end view of a rocking beam and appurtenances forming part of the mechanism whereby the bellows are operated and a music sheet, card, or tablet is fed. Fig. 11 is a front view of the same parts. Fig. 12 is a plan of a portion of the case of the instrument, which is located just below the dotted lines x x , Fig. 5. Fig. 13 is a perspective view illustrating certain positions of the frame. Fig. 14 is a side view of the motor of the instrument. Fig. 15 is a front view thereof, and Fig. 16 is a detail view, on an enlarged scale, of the brake on shaft H^2 .

Similar letters of reference designate corresponding parts in all the figures.

The sound-producing devices of the instrument may be of any suitable kind. I have not attempted to show them in full, as my improvement is not confined either to any special construction or arrangement of them. I have shown but a few sound-producing devices, consisting of pipes A . They are severally operated by a pneumatic motor, A' . The pneu-

matic motor A' , when operated, opens the valve A^2 , controlling communication between a pipe, A and the wind-chest W , and thereby admits air to the pipes. Some of the sound-producing devices will need to have their valves operated thus by a train of pneumatic motors, while others may have their valves operated by single motors. The valve of each single motor whereby the operation of a note is effected, and the valve of the master-motor of each train of motors whereby the operation of a note is effected, is operated by an electro-magnet, B . To this end the armature B' of each electro-magnet is mounted on a lever which is connected to the valve of the motor which the electro-magnet controls.

B^2 designates the battery or other source of electricity whereby the electro-magnets B are energized. The electro-magnets B are arranged in separate electric circuits or in separate branches of an electric circuit. The separate electric circuits or circuit-branches are normally open, and may be completed either through manual keys or by an automatic action controlled through a traveling music sheet, card, or tablet. I will explain these means separately. One wire, b , of an electric circuit or circuit branch is connected to one pole of the battery or other source of electricity, and the other wire, b' , leads to a metal strip, b^2 , on a bar, b^3 , which is connected to the key-board C . Over this metal strip b^2 extend the keys C' , which may be fulcrumed to the key-board and normally impelled upward at the forward ends in the usual manner. Under each key is fastened to the bar b^3 a metal plate, b^4 , which is insulated from the metal strip b^2 in any suitable manner. Each of the said metal plates b^4 is provided on the under side with a contact-piece of platina or other suitable metal, and immediately below the contact-piece of each of these plates the metal strip b^2 is provided with a corresponding contact-piece. Each key is provided on the under side and near the forward end with a lifter, b^5 , which engages with the corresponding plate, b^4 , and, when the forward end of the key moves upwardly, raises and holds its plate b^4 in an elevated position, thereby breaking contact between the contact-piece of that plate b^4 and the opposite contact-piece of the metal strip b^2 . The metal plate is elevated only at the

final upward movement of the forward end of the key; hence it is elevated very slightly. Owing to this the initial downward movement of the forward end of the key allows the contact-piece of the metal plate to make contact with the opposite contact-piece of the metal strip, and this contact continues until just before the key reaches its highest position. The shanks of the lifters are preferably 5 threaded, so that they may be inserted farther into the keys or moved farther out of the same, to vary the action of the lifters. The key-board C is connected at the rear end by 10 hinges C² to a stationary block, C³; hence it may be swung upward to facilitate access to the parts under it. From each of the metal plates b⁴ a wire, b⁵, extends to a pair of metal washers, c c', that are arranged upon what I term a "connection-bar," C⁴, because on it 15 are made numerous connections of the electric circuits or circuit branches. This wire b⁶ passes through a hole in the connection-bar to the top thereof, and is then passed up through one hole in the washer c, then over 20 the top and down through another hole. A wire, b⁷, has its end passed down through a hole in the upper washer, c', then along the under side to a second hole, then up through this second hole, and it is fastened to the main 25 part of the wire. This wire leads to one of a series of metallic spring-fingers or readers, D, in the automatic action before referred to. A wire, b⁸, extends between the washers. The portions of the wires b⁶ and b⁷ which extend 30 between the holes in the washers through which they are passed, and the portions of the wire b⁸ that extends between the washers, are disposed like the three sides of a triangle. The two washers are secured to the connection-bar 35 by a screw, c², passing through them into the connection-bar. The washers have notches in their peripheries that engage with a pin, c³, whereby they are prevented from shifting out of their proper relative positions. Electric 40 connections are thus made between the wires in such manner that the wires may be easily separated or united. It will be understood 45 that there is a wire, b', for each of the spring-fingers or readers. The spring-fingers or readers 50 are secured at one end to a rail, D', forming a common support, and at the other end are bent over and adapted to make contact with a metal bar or roller, E. A wire, b⁹, extends from this roller E to the wire b' or to the battery or 55 other source of electricity. A traveling music sheet, card, or tablet, which preferably is made of flexible paper, is passed between the spring-fingers or readers D and the roller E, and is provided with perforations, which allow 60 the spring-fingers or readers to make contact with the roller E, one or more at a time, as may be necessary to cause the playing of a tune. When the automatic action is not to be used, the spring fingers or readers are re- 65 tracted so that none will make contact with the roller E. The manner of securing this action of the spring-fingers or readers will

presently be explained in detail. When the spring-fingers or readers are retracted so that they cannot make contact with the roller E, 70 the electric circuits or circuit branches will be severally operative from the battery or other source of electricity through a wire, b', to a strip, b², thence to a plate, b⁴, thence along a wire, b⁶, to a washer, c, thence to a wire, b⁸, 75 thence to the coils of an electro-magnet, B, and thence by a wire, b, to the battery or other source of electricity. When the keys are not used and the spring-fingers or readers are rendered capable of making contact with the roller E, the electric circuits or circuit branches will severally be operative from the battery or other source of electricity along a wire, b⁹, to the roller E, thence to one of the spring-fingers or readers, thence along a wire, b⁷, to a pair 80 of washers, c c', thence along a wire, b⁸, to an electro-magnet, B, and thence along a wire, b, to the battery or other source of electricity. It will thus be seen that the electro-magnets may 85 be energized either by actuating the manual 90 keys or by the action of the spring-fingers or readers under control of the traveling music-sheet. If covered with insulating material, the 95 wires b may be bunched together in a cable. A wire common to the bunches of wires b and the wire b' may extend to an automatic circuit-breaker connected with one of the bellows of 100 the instrument in a manner hereinafter to be described, so that when the instrument is not in use electricity will not be wasted. Preferably, the pairs of washers c c' will be arranged 105 on the connection-bar in two rows, with those of one row opposite the spaces between those of the other row, so that each pair shall be at a considerable distance from adjacent pairs. 110 The spring-fingers or readers are preferably made of steel or other resilient wires, and so secured to their support that they will normally have a tendency to spring away from the roller E. Their ends which act upon the 115 roller E extend between the teeth of a comb, F, of insulating material, and are thereby guided and protected. When the spring-fingers are retracted, so that they cannot make contact with the roller E, their ends recede into the spaces between the teeth of the comb F, and hence are protected, so that the music-sheet may be 120 adjusted without injury to them.

G designates a presser-bar extending across the middle portion of the spring-fingers or readers and attached to a standard, G', that is connected at the lower end by hinges d to a fixed rail, G².

G³ are arms, which at the upper ends have connected to them a horizontally-extending rod, d', that is connected to the rear side of the standard G'. On the fronts of the arms G³, near the lower ends, are springs G⁴, that bear against screws G⁵, extending from the standard G'. 125

G⁶ are rods, which, near one end, have slots fitting the pins d', and near the other end are pivotally connected to levers G'. By moving the levers G' in one direction the arms G³ are 130

drawn over toward the levers. The standard G' is then also drawn in the same direction, so that the presser-bar G will press the free ends of the spring-fingers or readers toward 5 the roller E. The arms G³ have journaled to their upper ends a roller, G⁸, between which and a roller, G⁹, the traveling music-sheet is moved along. By thus drawing over the arms G³ forward the roller G⁸ is caused to press 10 against the roller G⁹ or against the music-sheet. Owing, however, to the manner in which these arms are supported, their lower ends can move to relieve this pressure, the arms swinging on the rod d' as fulcra. The 15 springs G⁴, acting on the screws G⁵, will, however, force the roller G⁸ toward the roller G⁹ with a yielding pressure.

By reversing the levers G⁷ the spring-fingers or readers will be relieved of pressure, so that 20 their free ends can recede into the comb, and the roller G⁸ will be moved away from the roller G⁹. It will be seen that the spring-fingers or readers will be forced out and the roller G⁸ forced toward the roller G⁹ simultaneously, and that they will be retracted when 25 the roller G⁸ is moved away from the roller G⁹. The music-sheet is guided by rails G¹⁰, which are connected with the comb, whereby the spring-fingers or readers are guided so that 30 the music-sheet and the spring-fingers or readers will maintain their proper relative positions. The roller G⁹ has on one of its journals a worm-wheel, G¹¹, that derives rotary motion from a worm, H¹, on a shaft, H, Fig. 35 2. The shaft H at the lower end fits into a socket formed in a bevel-wheel, H³, mounted on a shaft, H². At the top this socket has a spiral slot, e, extending a short distance upward, and the shaft H has a pin, e', that will 40 engage with the slot e when the shaft H² is rotated in the direction in which the shaft H should be rotated to propel the music-sheet. When, however, the shaft H is rotated by some means other than the shaft H² in the 45 proper direction to propel the music-sheet, it will not impart motion to the shaft H², because the upper end of the slot e will then move away from the pin e'. It is also true that if the shaft H² is rotated in the wrong direction 50 it will fail to impart motion to the shaft H, for then the closed end of the slot e will be moved away from the pin e', instead of toward it. The shaft H² has motion imparted to it from a motor that is operated by the feet of 55 the player. The bevel-wheel H³ engages with a bevel-wheel, H⁴, which is loosely mounted on a shaft, H⁵. This shaft H⁵ extends to the front of the key-board section of the case of the instrument in which the key-board and 60 keys are contained. The bevel-wheel H⁴ has a collar that is provided with a spiral slot, e², extending from the outer edge inward, and the shaft H⁵ has a pin, e³, that will engage with the slot e² when the shaft H⁵ is moved 65 properly to impart motion to the shaft H in the right direction. When, however, the shaft H⁵ is turned in the wrong direction, no motion

will be transmitted by it to the bevel-wheel H⁴, and when motion is transmitted to the shaft H by the shaft H², no motion will be 70 transmitted through the gear-wheel H⁴ to the shaft H⁵. The shaft H⁵ has the outer end made polygonal or is otherwise adapted to have a hand-crank interlocked with it. Provision is therefore afforded for operating the 75 shaft H by hand-power or by foot-power.

I will describe a motor by which the shaft H² may be rotated. I is a horizontally-arranged shaft, provided with a bevel-wheel, I', that engages with a bevel-wheel, H⁶, on the 80 shaft H². On the shaft I is loosely mounted a clutch-wheel, I², having passed around and fastened to it a strap, I³, that is also passed around and fastened to the periphery of a spring-barrel, I⁴. In the spring-barrel is a 85 convolute spring that is fastened at one end to the interior of the barrel and at the other end to a shaft, I⁵, on which the barrel is loosely mounted. When the clutch-wheel I² is moved in one direction, it rotates the spring-barrel so as to unwind the spring, and when the spring is permitted to wind up the clutch-wheel is moved in the other direction. It will 90 be understood that the spring, and not the lever I⁶, imparts motion to the shaft H², and hence effects the feed of the music-sheet. Owing to this, the music-sheet will be moved with 95 great uniformity. The tension of the spring may be varied by winding it more or less. It may be wound by turning with a key a shaft, 100 I⁶, that is provided with a worm, f, engaging with a worm-wheel mounted on the shaft I⁵.

I have combined with the spring-barrel I⁴ an indicator, whereby the amount of tension put upon the spring can be ascertained at any 105 time. This indicator consists of a tape-measure, I¹⁶, wound upon a spring-actuated roller in a case, I¹⁸, in a well-known manner, and having the outer end attached to a pulley, I¹⁵, that is affixed to the shaft I⁵. When this shaft 110 is turned around so as to wind up the spring, more of the tape-measure will be drawn out, and when the shaft is turned in the reverse direction part of the tape-measure will recede into the case I¹⁸. The clutch-wheel I² is provided internally with a number of faces, f', that are eccentric to the shaft I. Between the faces f' of the clutch-wheel and the shaft I are interposed balls or rollers f², of india-rubber, metal, or other suitable material. When the 115 clutch-wheel is rotated in the proper direction to unwind the spring of the spring-barrel, its faces f' do not clamp the balls or rollers f² against the shaft I; but when the spring in winding moves the clutch-wheel in the opposite direction the faces f' clamp the balls or rollers against the shaft and cause the shaft to be turned with the clutch-wheel. The shaft I is provided with a fly-wheel, I', which causes it to rotate not only while the clutch-wheel imparts motion to the shaft I, but also while the clutch-wheel rotates in the opposite direction. The clutch-wheel has a strap, I⁵, passed 120 around it in the reverse direction to the strap 125

I⁸. The strap I⁸ is fastened at one end to the clutch-wheel and at the other end to a lever, I⁹. The lever I⁹ is fulcrumed at or near the front end to the case or frame of the instrument, and has the strap I⁸ fastened to it at the rear end. This lever is arranged under a pedal, I¹⁰, and is depressed whenever the pedal is depressed. If desirable, however, the lever I⁹ may be depressed and fastened down by a hinged button, I¹¹, engaging with the rear portion of the lever. This will generally be done when the instrument is being played manually or by means of the shaft I⁵. The button I¹¹ constitutes a detent. It may be swung by the foot to one side or the other. When moved in one direction, while the lever I⁹ is depressed, it will engage with an extension of the lever and lock it, and when moved in the reverse direction it will be disengaged from the lever. Two stops, I¹⁷, are arranged at opposite sides of the lever to prevent it from being moved too far. There is a second pedal, I¹⁰, similar to the one already described. Each of these pedals has connected to it a strap, I¹², that transmits motion to a lever or rocking beam, I¹³. As shown, each lever or rocking beam consists of a rock-shaft, an arm near the front end thereof, and an arm near the rear end thereof. Each strap I¹² connects with the arm of a lever, I¹³, which is near the front end of the rock-shaft of the lever. The arm at the rear of the shaft of each lever connects with a strap, I¹⁴, that is fastened to the movable board of one of the feeders or bellows J of the instrument.

I have shown a lever, J', fulcrumed to a frame forming part of a reservoir, J², and connected at one end by a rod, J³, to the fixed board thereof, and at the other end by a rod, J⁴, to the upper movable board thereof, so as to form an evener or equalizer. Where pipes are used in the instrument, force-bellows will be employed. The bellows will not only operate the sound-producing devices, but will also operate the pneumatic motors, before referred to.

I will now describe a peculiar means of connecting the straps I¹² and I¹⁴ to the lever or rocking beams I¹³. On each arm of the beam is fitted a block, g, which has a groove around its circumference. Pins g' pass through the blocks and the arms of the lever or beam. The straps fit in the grooves of these blocks and hold the pins g' in position. By slackening the straps the pins may be withdrawn and the blocks slipped off the arms of the lever-beam. Preferably the straps have upper loop-shaped sections that are made separately and pivotally connected by rivets h.

Preferably, I combine with the shaft H² a brake, whereby its speed may be varied. The brake I have shown consists of a block, L, having a hole flaring from the middle toward each end and fitting the shaft H². As shown, this block has a removable face-plate, which may be detached to facilitate the removal from and application of the block to

the shaft. At one end this block is provided with a leg, L', that rests on a fixed block, L². The other end of the block passes through a slotted hanger, L³, in which it is guided, and receives just beyond this hanger a pin extending from a bell-crank lever, L⁴, which is fulcrumed to a pin, l. The lower end of this lever L⁴ bears upon a spring, l', extending from the block L. The upper end of the lever is connected to the drawer-pull L⁵. By pulling this drawer-pull the lever acts on the block with a yielding pressure and cant the latter more or less, thus causing it to grip and retard the motion of the shaft H². When the drawer-pull is released, a spring, l², attached to the lever, adjusts the latter into its normal position, and the block then releases the shaft H². By manipulating this drawer-pull the speed of the shaft H², and consequently the speed at which the music-sheet travels, may be varied and the expression of the playing changed. One of the main wires of the electric circuit is preferably interrupted or severed, and has its ends fastened to metallic contact-plates i i'. These contact-plates are secured near one end to a supporting-block, and are free at the other end. A piece of paper or other suitable material, i², is interposed between them at the end where they are secured to the supporting-block, but at the free ends they can and will make electrical contact, so as to complete the circuit when not separated by some ulterior force. When the bellows are in operation, these contact-plates will touch each other; but when the bellows are exhausted or collapsed the rod J⁴, arranged on the movable frame of the reservoir, will force the lower contact-plate away from its fellow and break the electric circuit. Thus the electric circuit will be automatically broken when the instrument is not in use, and the battery which supplies electricity for the instrument will not be consumed, except when needed. Any projection on the frame of the reservoir could be used to operate the plate i'.

Having now described the mechanism of this instrument, I will explain some features of its case. The main section of the case has four corner-posts, K, which are L-shaped in the cross-section. They extend from the bottom to the top of this section of the case. Caster-blocks K' are fastened to their lower ends. They support the entire weight of the main section of the instrument. Front panels, K², are rabbeted at the top, so that they hook over the rabbeted upper ends of these posts, and are provided with pins k, with which hook-like latches k', pivoted to the posts, engage. These front panels are thus secured in place, so that they can be readily detached when desirable. Side or end panels, K³, are rabbeted so that they can be hooked over the rabbeted upper ends of the post. When in place, they hold the latches k' in engagement with the pins k. At the lower ends the panels K² K³ have dowel-pins k', that enter holes in a fixed portion, K⁴, of the main section of the case and secure these

ends of the said panels in place. The side panels may be fastened down by bolts or otherwise, if desirable, to prevent them from being accidentally moved upward and detached.

5 The key-board section K^5 of the case is preferably made detachable from the main section of the case, so as to facilitate the transportation of the instrument and its passage through narrow doorways. This key-board section is 10 fastened to the main section by plates k^3 , made preferably of iron, secured by screws or otherwise to the key-board section, extending behind the fixed portion K^4 of the main section, and secured to the latter by screws or 15 other means. The key-board section is also secured to the main section of the case by metal angle-pieces k^4 , fastened to the two sections by screws or other suitable devices. When the key-board section is detached from 20 the main section of the case, it will be necessary to unfasten the wires that lead to it, and also to detach the straps I^2 from the levers I^3 . The front of the key-board section is provided with a removable panel, K^6 . One 25 end of this is rabbeted and enters a groove in one edge of the opening in which the panel fits. The other end is also rabbeted and engages with a reversely - rabbeted edge of the said opening. Near the latter edge the panel 30 is provided on the rear side with a lever-button, k^5 , rigidly affixed to a pivot-pin that extends through the panel and at the front is provided with a handle, whereby the lever-button may be rocked. The free end of this 35 button-lever acts in conjunction with a block, k^6 , arranged inside the key-board section. A spring, k^7 , normally holds the button-lever in contact with the block k^6 . While the button-lever is thus engaged with the block, the 40 panel cannot be moved longitudinally; but when the button-lever is swung out of the way of the block the panel can be moved longitudinally for the purpose of either removing it or securing it in place. In securing 45 it in place, the end near which the button-lever is pivoted is inserted so as to permit the engagement of the other end with its groove, and then the panel is pulled forward and the button-lever released. In removing the panel 50 the button-lever is swung aside, the end of the panel near which it is pivoted is pushed back, and then moved toward the block k^6 , then the other end of the panel is disengaged from its groove, and the panel is drawn out. The 55 reader-box K^7 , in which the readers or spring-fingers D and the parts adjacent thereto are arranged, has a front or cover that is connected to a rail, k^8 , on the key-board section of the case by hinges k^9 ; hence it may be thrown forward when desirable—as, for instance, while the instrument is playing mechanically or automatically.

The music-sheet which I employ will preferably be made in sections capable of being folded, and when such a music-sheet is used I 65 shall provide the inner side of the cover of the reader-box with rails k^{10} , between which

the music-sheet in a folded condition will be held. When the cover of the reader-box is closed, it may be fastened by a bolt, k^{10} . Plates k^{11} are fastened to the bottom of the reader-box and extend over the rail k^8 . The portions of these plates that extend over the rail k^8 have holes in which fit pins k^{12} , affixed to the lower edge of the cover when the cover is closed and the reader-box is in its normal upright position. When the parts are thus combined, the reader-box will be secured to the rail k^8 . The reader-box may be additionally secured in an upright position by hooks arranged upon it and engaging with the main section of the case, if desirable. It is desirable to provide for the detachment of the reader-box in order that access to the connection-bar C^4 and adjacent parts may be facilitated. The shaft H is removed from the 85 socket of the bevel-wheel H^3 when the reader-box is removed.

I do not herein claim, broadly, the detachable key-board section and the means for making electrical connection therewith herein 90 shown and described; neither do I claim, broadly, the special electric circuit-closer in the manner which I have shown and described, as I intend to make these the subject of another application for Letters Patent. 95

What I claim as my invention, and desire to secure by Letters Patent, is—

1. In a musical instrument adapted to be played mechanically, the combination of readers or spring-fingers, a driving-roller whereby a traveling music-sheet will be moved past the ends of the readers or spring-fingers, a pressure-roller and levers whereby the readers or spring-fingers will be forced forward and the pressure-roller moved toward the 105 driving-roller, substantially as specified.

2. In a musical instrument adapted to be played mechanically, the combination of a comb, readers or spring-fingers secured in place so that they will not normally protrude 110 through the comb, and a presser-bar whereby they may be made to protrude through the comb, substantially as specified.

3. In a mechanical musical instrument adapted to be played mechanically, the combination of readers or fingers automatically movable in one direction, a presser-bar for moving them in the other direction, a traveling music-sheet controlling the movements of the said readers or fingers, and a driving-roller whereby a traveling music sheet will be moved past them, substantially as specified. 115

4. The combination of the readers or spring-fingers D, the comb F, the bar G, and the adjustable standard G^4 , substantially as specified. 120

5. The combination of the readers or spring-fingers D, the comb F, the bar G, the adjustable standard G^4 , the levers G^5 , and the rods G^6 , substantially as specified.

6. The combination of the arms G^3 , the roller G^8 , the rods G^6 , and the levers G^5 , substantially as specified. 130

7. The combination of the readers or spring-fingers D, the bar G, the adjustable standard

G', the arms G³, the roller G⁸, the rods G⁶, and the levers G⁷, substantially as specified.

8. The combination of a comb, F, whereby readers or spring-fingers D are maintained in 5 their proper relative positions, and rails G¹⁰, connected to the same support as the said comb, and serving to guide a traveling music sheet, card, or tablet, whereby the readers or spring-fingers are controlled, substantially as specified.

10 fied.

9. In a musical instrument, the combination of the roller G⁹, provided with a worm-gear, G¹¹, of a removable shaft, H, provided with a worm, H', and the shaft H², substantially as 15 specified.

10. In a musical instrument, the combination of a shaft, H², means for driving the same, a shaft, H, and a connection between these shafts, whereby the former will impart rotary 20 motion to the latter when moved in one direction only, substantially as specified.

11. In a musical instrument, the combination of a shaft, H, a shaft, H⁵, bevel-wheels H³ and H⁴, and a connection between the shaft H⁵ 25 and its bevel-wheel H⁴, whereby this shaft will impart motion to its bevel-wheel when moved in one direction only, and whereby its bevel-wheel may be rotated without imparting motion to it, substantially as specified.

30 12. The combination of a pedal, I¹⁰, for operating bellows, a lever, I⁹, whereby a traveling music sheet, card, or tablet may be propelled, and a button, I¹¹, substantially as specified.

35 13. The combination of a pedal, I¹⁰, for operating bellows, a lever, I⁹, whereby a traveling music sheet, card, or tablet may be propelled, a button, I¹¹, and stops I¹⁷, substantially as specified.

40 14. In a musical instrument, the combination of a pedal, a lever or rocking beam for imparting motion to bellows, a block fitted to said beam, a pin passing transversely through the beam and block, and a strap having a loop 45 surrounding the block and securing the pin in place, substantially as specified.

15. In a musical instrument, the combination of a pedal, a lever or rocking beam for imparting motion to bellows, a block fitted to 50 said beam, a pin passing transversely through the beam and block, and a strap having hinged to it a loop, which surrounds the block and secures the pin in place, substantially as specified.

55 16. In a musical instrument adapted to be played mechanically, the combination of a rotary shaft, a clutch upon said shaft adapted when rotating in one direction to impart motion to the shaft and to run free of the shaft 60 when rotating in the other direction, a spring-motor connected with said clutch and serving to rotate the clutch in such direction that the latter will impart motion to the shaft, and a lever for intermittently operating the spring-motor to store up power therein, substantially as specified.

65 17. In a musical instrument, the combina-

tion of a driving-shaft, I, a clutch-wheel, I², adapted when moved in one direction to impart motion to the driving-shaft and to move free of the shaft in the reverse direction, a lever, I⁹, a strap, I⁸, connecting the lever I⁹ to the clutch-wheel I², a spring-barrel, I, and a strap, I³, connecting the spring-barrel with the clutch-wheel, substantially as 75 specified.

18. In a musical instrument, the combination, with the shaft I⁵ of the spring-barrel I⁴, of the worm-wheel I¹⁵ on the shaft I⁵, and the shaft I⁶, provided with the worm f, substantially as specified.

19. In a musical instrument, the combination, with the spring-barrel I⁴ and the shaft I⁶, whereby the shaft of the spring-barrel may be turned to vary the force of the spring in 85 the spring-barrel, of the tape-measure I¹⁶ and a case, I¹⁸, containing a spring-actuated roller, to which the tape-measure is attached, substantially as specified.

20. In a musical instrument, the combination of a shaft whereby the propulsion of the traveling music sheet, card, or tablet will be effected, a brake-block provided with a hole flaring from the middle toward each end and fitting said shaft, a lever for operating 95 said brake-block in one direction to grip said shaft and retard its motion, and a drawer-pull for actuating the lever, substantially as specified.

21. In a musical instrument, the combination of the shaft H², whereby the propulsion of the traveling music sheet, card, or tablet will be effected, the brake-block L, provided with the leg L', the fixed block L², the slotted hanger L³, receiving the brake-block, the lever L⁴, provided with a pin extending into the brake-block, the spring l, extending from the brake-block, and upon which one end of the lever L⁴ bears, and the drawer-pull L⁵, substantially as specified.

22. In a mechanical musical instrument, the combination, with electric circuit-wires, of contact plates or pieces i i', an extensible and contractile reservoir, and a rod or projection for separating the said contact plates or pieces 115 when the reservoir is collapsed, substantially as specified.

23. In the case of a musical instrument, the combination of the corner posts, K, the front panels, K², the pins and latches k k', and the 120 side panels, K³, substantially as specified.

24. The combination, with the key-board section K⁶, of a hinged cover, the rail k⁸, the plates k¹¹, and the pins k¹², substantially as specified.

25. The combination, with the key-board section of a musical instrument, of a reader-box secured thereto so that it can be moved forward and a detachable shaft extending into the reader-box, substantially as specified.
